US0D1035842S

(12) **United States Design Patent** (10) Patent No.: **US D1,035,842 S**
(45) Date of Patent: ** Jul. 16, 2024

(54) **RAISED DIRECTIONAL INDICATOR FOR A FIRE HOSE COUPLING**

(71) Applicant: **Elmer F. Williams, II**, San Antonio, TX (US)

(72) Inventor: **Elmer F. Williams, II**, San Antonio, TX (US)

(**) Term: **15 Years**

(21) Appl. No.: **29/875,273**

(22) Filed: **May 2, 2023**

Related U.S. Application Data

(62) Division of application No. 29/805,891, filed on Aug. 31, 2021, now Pat. No. Des. 996,583.

(57) **CLAIM**

The ornamental design for a raised directional indicator for a fire hose coupling, as shown and described.

DESCRIPTION

FIG. 1 is a perspective view of the ornamental design.

FIG. 2 is a top view of the ornamental design.

FIG. 3 is a bottom view of the ornamental design.

FIG. 4 is a front view of the ornamental design.

FIG. 5 is a rear view of the ornamental design.

FIG. 6 is a left view of the ornamental design; and,

FIG. 7 is a right view of the ornamental design.

The broken lines in the drawings are included to show the environment related to the claimed design and form no part of the claimed design.

1 Claim, 7 Drawing Sheets
